Robert Burns

ATTORNEY.

UNITED STATES PATENT OFFICE.

PHINEAS A. BENNETT, OF CHICAGO, ILLINOIS, ASSIGNOR OF ONE-HALF TO
THOMAS BENNETT, OF SAME PLACE.

SIGHT-FEED LUBRICATOR.

SPECIFICATION forming part of Letters Patent No. 390,584, dated October 2, 1888.

Application filed May 31, 1888. Serial No. 275,636. (No model.)

To all whom it may concern:

Be it known that I, PHINEAS A. BENNETT, a citizen of the United States, residing at Chicago, in the county of Cook and State of Illinois, have invented a certain new and useful Improvement in Sight-Feed Lubricators; and I do hereby declare the following to be a full, clear, and exact description of the same, reference being had to the accompanying drawings, forming part of this specification.

This invention relates to that class of lubricating oil-cups in which the oil flows by gravity down through a transparent chamber in its passage from the oil-reservoir to the bearing to be lubricated.

The present improvement has for its object to provide a cup which as a whole is durable and effective in operation and cheap and simple in construction. I attain such object by the construction and arrangement of parts illustrated in the accompanying drawings, in which—

Figure 1 is an elevation of a lubricator constructed in accordance with my invention, and Fig. 2 a vertical axial section of the same.

Similar letters of reference indicate like parts in the several views.

Referring to the drawings, A' represents the cylindrical glass body of the oil-reservoir A, arranged between the upper and lower flanged heads, B C, the joints between the parts being rendered tight by annular elastic washers D D' and vertical tie-bolts D², that pass down through the interior of the oil-chamber. Such bolts are headed on their upper ends, while their lower ends screw into upwardly-projecting bosses d on the lower head, C, as shown.

E is the valve for regulating the flow of the oil from the oil-chamber. This valve is of the needle type, arranged axially in the oil-chamber, its lower or valve end being seated on the upper end of the outlet oil-passage e in the lower head, C, and its upper end provided with a handle or knob, F', by which it is adjusted. Its longitudinal movement is effected by its intermediate screw-threaded portion, E², screwing in the axial screw-threaded ori-

fice of the upper head, B, B' being a packing-gland, by which a tight joint is formed around the valve-stem and the proper amount of frictional resistance furnished to afford a sensitive adjustment of the valve.

F is the visible-feed chamber arranged below the oil-chamber, and consisting of a section of glass tubing, G, inclosed in a slotted tubular metal cage, H, the lower end of which is formed with a screw-threaded shank, H', for attachment to the bearing, and having passage L leading from the sight-feed chamber F to the journal or bearing, while its upper end is enlarged and internally screw-threaded to screw upon an attaching-neck, I, on the under side of the head C.

The glass tube G rests upon the bottom of the cage, its upper end being packed or held by an annular gasket, J, arranged between the lower face of the neck I and the offset h in the cage, as shown. i is an annular recess in the neck I, to receive the end of the glass tube G, projecting above the packing J.

K is the pendent nipple, through which the oil is delivered in drops down through the visible-feed chamber F. Such nipple is axially arranged, and is attached in place by being screwed into the under side of the lower head, C.

M is the hinged cover closing the filling- orifice of the oil chamber or reservoir.

Having thus fully described my said invention, what I claim as new, and desire to secure by Letters Patent, is—

The combination, with the oil-chamber A, the lower head of which is provided with an attaching-neck, I, having annular groove i and attached nipple K, of the cage H, having attaching shank H' and offset h, gland-packing J, and glass tube G, as described, and for the purpose set forth.

In testimony whereof witness my hand this 22d day of May, 1888.

PHINEAS A. BENNETT.

In presence of—

C. MARCHAND,
ROBERT BURNS.
